(57) **CLAIM**

The ornamental design for an LED light bulb, as shown and described.

DESCRIPTION

Embodiment 1:

FIG. 1 is a perspective view thereof;
FIG. 2 is a front view thereof;
FIG. 3 is a rear view thereof;
FIG. 4 is a plan view thereof;
FIG. 5 is a bottom plan view thereof;
FIG. 6 is a right side view thereof; and
FIG. 7 is a left side view thereof.

Embodiment 2:

FIG. 8 is a perspective view thereof
FIG. 9 is a front view thereof;
FIG. 10 is a rear view thereof;
FIG. 11 is a plan view thereof;
FIG. 12 is a bottom plan view thereof;
FIG. 13 is a right side view thereof
FIG. 14 is a left side view thereof.

Embodiment 3:

FIG. 15 is a perspective view thereof
FIG. 16 is a front view thereof;
FIG. 17 is a rear view thereof;
FIG. 18 is a plan view thereof;
FIG. 19 is a bottom plan view thereof;
FIG. 20 is a right side view thereof; and,
FIG. 21 is a left side view thereof.

The design of the LED light bulb relates to a light emitting diode (LED) light bulb including an LED serving as a light source. A light emitted from the LED is diffused by embossed marks of the light guide plate to emit an illumination light.
